UNITED STATES PATENT OFFICE

99,900

DESIGN FOR A GOBLET OR SIMILAR ARTICLE

Dixon Connolly Sloan, Cumberland, Md., assignor to United States Glass Company, Pittsburgh, Pa., a corporation of Pennsylvania

Application March 31, 1936, Serial No. 61,871

Term of patent 7 years

To all whom it may concern:

Be it known that I, Dixon Connolly Sloan, a citizen of the United States, residing at Cumberland, county of Allegany, in the State of Maryland, have invented a new, original, and ornamental Design for a Goblet or Similar Article, of which the following is a specification, reference being had to the accompanying drawing, forming a part thereof, in which—

I claim:

The ornamental design for a goblet or similar article, substantially as shown.

In witness whereof, I have hereunto set my hand.

DIXON CONNOLLY SLOAN.
